MUFFLER

Brewster G. Robbins, Utica, N. Y., assignor to
Herbert S. Powell, Utica, N. Y.

Application November 17, 1938, Serial No. 241,039

7 Claims. (Cl. 181—54)

The present invention relates to new and useful improvements in mufflers, and more particularly to improvements in mufflers which are generally used for quieting the noise incident to the exhaust of gases from internal combustion engines.

The invention is concerned generally with the provision of a muffler of the type which includes a plurality of tubes disposed within the muffler casing for causing the gases to pass therethrough in a circuitous path. The tubes extend through a plurality of baffle plates which divide the casing into a plurality of expansion chambers, and these tubes are preforated or slotted to permit the gases to expand into the expansion chambers during their passage through the muffler casing. Mufflers of this type are generally classed as "straight-through" or "tri-flow" types. In the first type, there is generally provided a perforated central tube which extends substantially through the muffler casing, and baffle plates are provided around the tube so as to provide a plurality of expansion chambers into which the gases can expand during their passage through the muffler. In the second type, a plurality of tubes are generally mounted within the muffler casing in parallel relationship so that the exhaust gases pass through the muffler casing in a sinuous and reversely directed path. These tubes also pass through baffle plates which afford expansion chambers into which the exhaust gases are successively expanded as they pass through the various tubes in the casing.

More particularly, the present invention is concerned with a muffler which includes a "tri-flow" portion or which includes both "straight-through" and "tri-flow" portions. It often becomes necessary to change mufflers, and for this purpose, it is desirable to provide a muffler which can be readily interchanged with already existing types of mufflers. When it is desired to substitute a "tri-flow" or combined "tri-flow" and "straight-through" muffler for some other type of muffler construction, it is difficult to provide an exact fitting within the muffler casing and with the exhaust pipe connections. The present invention is concerned with the provision of a muffler of this type which can be readily interchanged and which possesses certain novel characteristics and advantages.

An object of the present invention is to provide a muffler which is of relatively simple construction, which is inexpensive to manufacture, and which effects the desired quieting of the exhaust gases.

A further object of the invention is to provide a muffler of the above type, which is so constructed that it occupies a minimum amount of space and can be substituted for the usual type of "straight-through" muffler having a centrally located exhaust pipe connection.

A still further object of the invention is to provide a muffler which includes a plurality of parallel tubes providing a sinuous path for the exhaust gases, and wherein the parallel tubes are constructed so as to occupy a minimum amount of space within the muffler casing and, at the same time, permit the necessary freedom of movement of the gases therethrough.

A still further object of the invention is to provide a muffler of the above type, wherein one of the parallel tubes is centrally located and adapted for connection to the exhaust pipe connection, and wherein the side parallel tubes are arcuately shaped in cross section so as to permit their disposition in the limited amount of space between the central tube and the muffler casing.

The above and other objects of the invention will in part be obvious, and will be hereinafter more fully pointed out.

In the accompanying drawing,

Figure 1 is a side view, in section, showing the muffler assembly.

Figure 2 is an enlarged sectional view, taken along the line 2—2 of Figure 1.

Figure 3 is a similarly enlarged sectional view, taken along the line 3—3 of Figure 1.

Referring more in detail to the accompanying drawing, the muffler assembly is illustrated as including an outer muffler casing 10, which is provided with end closures or heads 11, 12. These end closures 11, 12 are provided with outwardly extending flanges 11a, 12a, respectively, which are suitably secured, as by welding, to the inner surface of the muffler casing. The end closures 11, 12 are illustrated as being centrally apertured and provided with inwardly extending flanges 11b, 12b, respectively, around the apertures therethrough. An inlet pipe connection 13 leading from the internal combustion engine (not shown) 45 has the inner end 13a thereof slightly offset and disposed within the flange 11b on the closure 11. An exhaust pipe connection 14 is provided with a similar offset end portion 14a which is disposed within the flange 12b on the end closure 12.

In the illustrated embodiment of the invention, a centrally disposed tube 15 has one end thereof suitably secured, as by welding, within the portion 13a of the inlet pipe connection 13. This tube 15 is perforated in any suitable manner, as

by the provision of groups of slots 16, and extends only partially through the muffler casing 10. A pair of spaced baffle plates 17, 18 are provided with outer flanges 17a, 18a, respectively, which are welded or otherwise secured to the inner surface of the muffler casing. These baffle plates 17, 18 are also provided with inner flanges 17b, 18b, respectively, which are secured around the tube 15. The baffle plates 17, 18 are also provided with an annular ring of apertures 17c, 18c, respectively. The end closure 11 and the baffle plate 17 define an expansion chamber A which communicates with the tube 15 through groups of slots 16 therein. Similarly, the baffle plates 17 and 18 define an expansion chamber B which is also in communication with the tube 15.

A centrally disposed tube 19 has one end 19a thereof suitably secured within the end portion 14a of the exhaust pipe connection 14 and extends through a relatively large portion of the muffler casing. At opposite sides of the central tube 19 there are provided tubes 20, 21 which are illustrated as being parallel to the central tube 19 and arcuately shaped in cross section, as particularly shown in Figure 3. The arcuate shaping of the tubes 20, 21, is taken substantially about the central axis of the tube 19. Thus, the tubes 20, 21 afford a relatively large interior conduit portion, but occupy a minimum amount of space so that they can be conveniently positioned between the muffler casing 10 and the center tube 19. The arcuate tubes 20, 21 are entirely separate units and independent of each other and of the central tube 19. The inner wall portions of the tubes 20, 21 are spaced outwardly from the central tube 19 and are parallel thereto, while the outer wall portions of the tubes 20, 21 are spaced inwardly from the adjacent inner surface of the muffler casing and are parallel thereto. Thus, the tubes 19, 20 and 21 afford separate conduits for the passage of gases.

Baffle plates 22, 23, 24, 25 are each provided with flanges by which they are suitably secured in spaced relationship to the interior surface of the muffler casing. These baffle plates are also apertured and properly shaped so that the tubes 19, 20, 21 can extend therethrough. Thus, there is provided an expansion chamber C between the baffle plates 22, 23, an expansion chamber D between the baffle plates 23, 24, and an expansion chamber E between the baffle plates 24, 25. The tube 20 is provided with groups of perforations in the form of slots 26 which afford communication between this tube and the expansion chamber C. The central tube 19 is provided with groups of slots 30 in the center portion thereof and these slots afford communication between this tube and the expansion chamber D.

The inner end 20a of the tube 20 is extended and a baffle plate 31 is provided with flanges 31b which are secured around the extended end of the tube 20. The baffle plate 31 is also provided with outer flanges 31a which are suitably secured to the inner surface of the casing 10. There is thus provided an intermediate expansion chamber F between the baffle plate 18 and the baffle plate 31. The baffle plate 31 prevents direct communication between the tubes 19, 21 and the chamber F, although the tube 20 is in communication with the chamber F. A chamber G is provided between the end closure 12 and the baffle plate 25, and this chamber provides communication between the tubes 20, 21. The end 19a of the central tube 19 extends through this cham-

ber and is not in direct communication therewith.

Gases entering the muffler through the pipe connection 13 are directed into the tube 15. A portion of these gases is expanded into the chambers A and B through the slots 16 during their passage through the tube. A portion of the gases expanded into the chambers A and B may also be directed through the openings 17c, 18c into the chamber F. The gases issuing from the inner end of the tube 15 are further expanded in the chamber F and then pass through the tube 20. During the passage of the gases through the tube 20, a portion thereof gains access to the expansion chamber C and then passes through the chamber G into the return tube 21. During the passage of the gases through the tube 21, a portion thereof is expanded into the expansion chamber E and then passes into the inner end of the central tube 19. The gases passing through the central tube 19 toward the exhaust pipe connection 14 are further expanded through the perforations 30 into the expansion chamber D.

From the foregoing description, it will be seen that the illustrated form of muffler includes a relatively short "straight-through" portion and a relatively long "tri-flow" portion. It is to be understood, however, that the "tri-flow" portion of the muffler may constitute the entire inner assembly. The present construction provides a muffler wherein a cylindrical tube within the muffler casing is adapted to be directly connected to the exhaust pipe connection of the muffler. The side tubes are shaped so as to occupy a minimum amount of space between the cylindrical tube and the muffler casing, thus providing an inner muffler assembly which may be substituted and placed within a relatively small muffler casing. The cylindrical tube may be positioned with respect to the side tubes so that it can be directly connected to the exhaust pipe connection. In the illustrated embodiment of the invention, the cylindrical tube is illustrated as being centrally disposed for attachment to a centrally disposed exhaust pipe connection. In this form of the invention, the arcuate-shaped side tubes are disposed at diametrically opposed points with respect to the center tube, and these side tubes are shaped about the central axis of the muffler casing so as to occupy a minimum amount of space between the center tube and the inner surface of the muffler casing. However, the side tubes, while arcuately shaped in cross section, are elongated so as to provide the desired internal area permitting the free flow of gases therethrough.

The illustrated form of muffler is one which may be connected to centrally disposed inlet and exhaust connections so that the gases are caused to pass in a sinuous and reversely directed path through a portion of the muffler. The baffle plate 31 prevents direct communication between the tubes 19, 21, and the inlet portion of the muffler, but permits the tube 20 to communicate therewith. The end closure 12 prevents direct communication between the tubes 20, 21 and the exhaust pipe connection, but permits the central tube 19a to be directly attached thereto.

While one form of the invention has been shown in the drawing, it is to be clearly understood that various changes in the details of construction and arrangement of parts may be made without departing from the scope of the invention as set forth in the appended claims.

I claim:

1. A muffler comprising a casing, a plurality of spaced baffle plates secured to the inner surface of said casing for providing expansion chambers, and a plurality of separate parallel tubes entirely independent of one another extending through said baffle plates for providing separate passages for the gases and being perforated to permit the passage of gases into said expansion chambers, one of said tubes being directly connected to an exhaust pipe connection, and the other of said tubes being arcuately shaped in cross section about the center axis of said first tube whereby the said tubes occupy a minimum amount of space within the casing.
2. A muffler comprising a cylindrical casing, a plurality of spaced baffle plates secured to the inner surface of said casing for providing expansion chambers, a centrally disposed cylindrical tube disposed within said casing and extending through said baffle plates, said tube being directly connected to an exhaust pipe connection, and a pair of separate side tubes entirely independent of each other and of said cylindrical tube and arcuately shaped in cross section about the central axis of said casing and disposed at diametrically opposed points with respect to said central tube, said tubes being perforated to permit passage of the gases into said expansion chambers and said side tubes having the inner wall portions thereof spaced outwardly from and parallel to the adjacent wall of said cylindrical tube and having the outer wall portions thereof spaced inwardly from and parallel to the inner surface of said casing.
3. A muffler comprising a casing, a plurality of spaced baffle plates disposed at one end of said casing for providing expansion chambers, a centrally disposed inlet tube extending through said baffle plates and being perforated to permit the passage of gases into said expansion chambers, a plurality of spaced baffle plates secured to the inner surface of the opposite end of the casing and providing additional expansion chambers, and a plurality of separate parallel tubes entirely independent of one another extending through the latter group of baffle plates and being perforated to permit the passage of gases into the latter group of expansion chambers.
4. A muffler comprising a casing, a plurality of spaced baffle plates disposed at one end of said casing for providing expansion chambers, a centrally disposed inlet tube extending through said baffle plates and being perforated to permit the passage of gases into said expansion chambers, a plurality of spaced baffle plates secured to the inner surface of the opposite end of the casing and providing additional expansion chambers, and a plurality of separate parallel tubes entirely independent of one another extending through the latter group of baffle plates and being perforated to permit the passage of gases into the latter group of expansion chambers, one of said parallel tubes being centrally disposed within said casing and directly connected to an exhaust pipe connection.

5. A muffler comprising a casing, a plurality of baffle plates secured to the inner surface of said casing for providing expansion chambers, a plurality of separate parallel tubes entirely independent of one another extending through said baffle plates and being arcuately shaped in cross section about the central axis of the casing whereby the said parallel tubes occupy a minimum amount of space within the casing.

6. A muffler comprising a casing, a plurality of baffle plates secured to the inner surface of said casing for providing expansion chambers, a centrally disposed cylindrical tube extending through said baffle plates and directly connected to an exhaust pipe connection and the other of said tubes being disposed between the tube connected to the exhaust pipe and said casing and arcuately shaped in cross section, and a partition wall disposed within the casing and through which one of said arcuate-shaped tubes extends for communication with the inlet end of the muffler, said partition wall preventing direct communication between the other of said tubes and the inlet end of the muffler.

7. A muffler comprising a casing, a plurality of baffle plates secured to the inner surface of said casing for providing expansion chambers, a centrally disposed cylindrical tube extending through said baffle plates and directly connected to an exhaust pipe connection, said tube being perforated intermediate the ends thereof for affording communication with one of said expansion chambers, and a pair of separate tubes disposed between said cylindrical tube and said casing and at diametrically opposed points with respect to said central tube and extending through said baffle plates, said parallel tubes being arcuately shaped in cross section about the center axis of said central tube with the inner wall portions thereof spaced outwardly from and parallel to the wall of said cylindrical tube and with the outer wall portions thereof spaced inwardly from and parallel to the inner surface of said casing and being perforated to afford communication with each of said expansion chambers.

8. A muffler comprising a casing, a plurality of baffle plates secured to the inner surface of said casing for providing expansion chambers, a centrally disposed cylindrical tube extending through said baffle plates and directly connected to an exhaust pipe connection, said tube being perforated intermediate the ends thereof for affording communication with one of said expansion chambers, and a pair of separate parallel tubes disposed between said cylindrical tube and said casing and at diametrically opposed points with respect to said central tube and extending through said baffle plates, said parallel tubes being arcuately shaped in cross section about the center axis of said central tube and being perforated at opposite ends whereby each will afford communication with another of said expansion chambers.
